[57] CLAIM

The ornamental design for a medical trolley, as shown
and described.

DESCRIPTION

FIG. 1 is a top and side perspective view of a medical
trolley showing our new design;

FIG. 2 is a partially exploded top and front perspective
view thereof;

FIG. 3 is a partially exploded top and rear perspective
view thereof;

FIG. 4 is a front elevation view therein; and,

FIG. 5 is a top plan view of the trolley.
